UNITED STATES PATENT OFFICE.

RICHARD A. OGLESBY, OF SOUTH BEND, INDIANA, ASSIGNOR TO QUICK ACTION IGNITION COMPANY, OF SOUTH BEND, INDIANA, A CORPORATION OF INDIANA.

COMBINED V-TYPE ENGINE AND MAGNETO.

1,282,114.

Specification of Letters Patent. Patented Oct. 22, 1918.

Application filed April 14, 1917. Serial No. 162,152.

To all whom it may concern:

Be it known that I, RICHARD A. OGLESBY, citizen of the United States, residing at South Bend, in the county of St. Joseph and State of Indiana, have invented certain new and useful Improvements in Combined V-Type Engines and Magneton, of which the following is a specification.

My invention relates to improvements in a combined V-type engine and magneto and it more especially appertains to the features pointed out in the annexed claims.

The purpose of my invention is to provide a direct connected magneto combined with a V type of multicylinder engine so that every portion of its cycle of rotating will be absolutely asynchronous with the movement of the engine crank shaft; that will provide a form of magneto which eliminates all the usual complexities of gear drive, etc., with its attendant uncertainties of continuous operation: that in the main is assemblable from standard parts equally adaptable to other types of engines thereby securing great economies in production and precise definiteness of operation.

With these and other ends in view I illustrate in the accompanying drawing such an instance of adaptation as will disclose the broad features without limiting myself to the specific details shown.

Figure 1 is a front elevation showing the angular relation of the cylinders to the armature coils.

Fig. 2 is a side elevation showing the direct connected relation of the crank shaft to the magneto magnet.

Fig. 3 is a diagrammatic relation of the circuit connections.

Fig. 4 is an end elevation partly in section showing the magnet-fly wheel relation to the armature, showing a plain central armature head common to both magnets.

Fig. 5 is an elevation showing all armature heads of the overhang type, the central head common to both magnets but with the magnets at different angles from that shown in Fig. 4.

Fig. 6 is an enlarged elevation showing the relation of isolated armature magnets and heads.

Fig. 7 is a plan view of the core and head portions of Fig. 5.

In ordinary practice when engines are grouped at an angle to each other to form

an N it is found exceedingly difficult to combine magnetos of the customary shuttle armature type to serve such engines because of the unsymmetrical angular displacements between the cylinder axes and the extreme 60 difficulty in harmonizing the speed of such magnetos with the speed of V type engines. When the V angle is some odd value as 51° the difficulty is practically insuperable. Even if the recurrence of the magneto impulses are made to synchronize with the firing periods of the interconnected cylinders the duration of such impulses in relation to the firing angle of the crank shaft becomes 65 so small as to seriously reduce the effectiveness of the impulses.

The difficulty with the ordinary type of magneto lies in the fact that a symmetrical magnetic field in relation to the axis of rotation is used, the maximum induction occurring 75 at each half revolution of the armature. With V type engines having the connecting rods of companion cylinders working on the same crank pin the irregularity on firing sequence is related to extent of their angular variation.

Various expedients have been devised to overcome these difficulties by building 60 degree armatures; shuttle armatures with alternate heads removed for one half of the 85 core length; by arbitrarily shaping the heads so as to in some measure compensate for the irregularity otherwise present as a handicap. With cylinders placed 90 degrees apart the difficulty is likewise serious because of the production of sparks in a pair of cylinders does not occur at the moment of maximum induction and besides there is no opportunity to control the spark either to advance or retard the explosion. To time 90 the spark recurrence with the firing points of the cylinders requires an excessive magneto speed or special construction at an excessive cost. Whatever results such expedients accomplish they are limited to V 100 type engines whose angle is a multiple of 360 degrees.

With an adaptation instanced in the accompanying drawing the difficulties recited disappear because the position of independent 105 coils is always asynchronous with the angular velocity of the crank pins of the engine shaft. It is immaterial at what angle the various exigencies of practice or design may place pairs of V type cylinders because 110

the separate coils of the armature are simply disposed accordingly so that there is an independent coil breaker, condenser, etc., for each leg of the V.

- 5 In Fig. 1 two engines 1 and 2 are shown in more or less diagrammatic relation to the armature coils 18 and 19. The angle between them is indicated by "a." A suitable base 5 is common to all the cylinders and 10 cranks 3 and 4 are a part of engine shaft 10. This shaft projects beyond the engine casting hub 9 sufficiently far to receive fly wheel hub 12 secured thereon in any suitable manner. The fly wheel rim 14 is connected to 15 the hub 9 by a web 11. When fly wheels are made of cast iron the magnet 17 should be supported some distance away to avoid excessive leakage across its air gap or a magnetizing ring 16 must be interposed between 20 it and the fly wheel rim or the adjacent portion of any other rotative member attached to the crank shaft 19 or one rotating at the same speed as such shaft.

The armature plate 6 in case of fixed ignition requirements may be secured to the engine casing 5 by means of distance sleeves 7 or equivalent projections and screws 27. When variable ignition positions are to be served the plate 6 may be rocked around 25 hub 9 to whatever degree is desired by link 36 shown in Fig. 6. This plate has a hub 8 which encircles hub 9 and if desired may have a set or clamping screw adapted to engage the hub 9 instead of screws 27 to hold 30 the plate in a fixed position. Since this is no part of my present invention it is not shown. The plate 6 has posts 15 on which circuit breakers are pivoted. These comprise arms 32 and elastic members 34 secured to hubs 31, coil springs in each case hold the members 34 against the contact screws of each primary circuit. The arms 32 are engaged by "cam" 33 attached to an annular plate 13 which encircles the hub 12 35 of the fly wheel.

The plate 6 also carries the armature coils 18 and 19. These coils are entirely independent of each other, one being supplied for each leg of the V of the engine assembly. 40 In addition condensers 35 are secured thereon so that the entire plate can be handled as a unit in assembling or dismantling an installation.

The cores and laminated heads of the 45 armature coils may be made separate as shown in Fig. 6 or they may have one head common to two coils as shown in Figs. 1, 4 and 5. When central head has no projecting ends as 26 in Figs. 1 and 4 the outer 50 heads 25 have very long projections in order to position the air gap in relation to the cylinders 1 and 2. If a central head is to also have projections as 23 in Fig. 5 then the laminated cores 24 are built up as a 55 part of the central head 23. The ends of

cores 24 are widened out into heads 21 as shown in Fig. 7. When heads 21 are used at both ends of each coil as shown in Fig. 6 a half core 20 may project from each head or the entire core member may project 70 from one head only, passing through the coil and into a recess of the other head. Where the parts are held together by any suitable means each unit coil with its core and heads is secured to plate 6 in any way 75 desired, a cavity is formed in the plate for each coil so as to provide clearance for the moving parts.

The field magneto 17 is provided with laminated pole ends 22 secured to the support 16 in close contact with the ends of the magnet which is also secured on this support. Armature coils 18 and 19 usually comprise a primary winding 28 and a secondary winding 29. The latter is connected 85 with spark plugs 30.

As this invention is of commanding importance its distinctive features are claimed in their broadest sense with a full inclusion of such modifications as the exigencies of 90 actual practice may demand.

What I claim is—

1. In V type engines, suitable cylinders disposed in pairs at an angle to each other, a crank shaft, a casing therefor having bearings therein, a relatively stationary armature support held in concentric relation to the main axis of the crank shaft, independent coils having suitable cores and heads attached to said support at such an angle to each other that their points of maximum induction coördinate with the angular position of the individual cylinders of each pair to each other, and a field magnet rotated by the crank shaft in working proximity to the coil heads. 100

2. In a combined magneto and internal combustion engine, a pair of cylinders disposed at an odd angle to each other, a crank shaft common to both cylinders, a casing therefor, bearings therein, a permanent field magnet having an air gap rotated by the shaft asynchronously therewith, a relatively stationary plate supported adjacent the path of travel of the magnet, independent coils having cores and heads secured to the plate and so disposed as to have their points of maximum induction coördinate with the angular position of the cylinders with respect to each other and the air gap of the 110 field magnet. 115

3. In internal combustion engines, one or more pairs of cylinders having the cylinders of each pair disposed at an angle to each other, pistons and attached connecting rods in the cylinders, a crank shaft rotated by the connecting rods through a movement of the pistons, a fly wheel rotated by the shaft at a synchronous angular velocity, a permanent magnet having an air gap there- 120 125 130

in suitably supported by the fly wheel, an armature support, independent coils thereon adapted to separately serve the cylinders on the separate pairs independently of each other, cores and heads to the coil proportioned with respect to the air gap of the magnet and so placed with respect to angular disposition of the cylinders as to coordinate their points of maximum inductive effect with the successive firing periods of the cylinders in proper sequence.

4. In internal combustion engines, a plurality of cylinders placed at an odd angle to each other on a plane parallel to the movement of pistons therein, a crank shaft, a casing therefor serving as a base for the cylinders, pistons in the cylinders, connecting rods between the pistons and cylinders, means moving in angular synchronism with the crank shaft adapted to produce the explosion of fuel charges in the respective cylinders in orderly sequence, and means adapted to advance or retard the time of ignition of the charges without interfering with the sequence or the efficacy thereof whereby each cylinder will be properly served independently of any other.

5. In internal combustion engines, a crank shaft, connections therefrom to a plurality of pistons, cylinders for the pistons placed at an angle to each other, a magnet

mechanically actuated by the crank shaft the same being adapted to progressively move a field of variable magnetic flux in a rotary plane, and inductive means placed within the path of travel of such flux said means being so coördinated as to serve the angular groups of the cylinders independently of each other with ignition currents in orderly sequence as the flux is swept across the inductive means.

6. In internal combustion engines, a crank shaft, connections therefrom to the pistons of a plurality of cylinders placed at an angle to each other with respect to the shaft, a field magnet rotated by the crank shaft while directly supported by said shaft the magnet being adapted to progressively move a field of magnetic flux in a rotary plane, and inductive means placed within the path of travel of such flux said means being so coördinated as to serve the angular groups of cylinders independently of each other in orderly sequence as the flux is swept across such means.

In testimony whereof I affix my signature in the presence of two witnesses.
